UNITED STATES PATENT OFFICE.

JOHN R. SPURRIER, OF BETHLEHEM, PENNSYLVANIA, ASSIGNOR TO ROLLER-SMITH COMPANY, A CORPORATION OF NEW YORK.

CIRCUIT BREAKER.

Application filed September 29, 1919. Serial No. 327,149.

To all whom it may concern:

Be it known that I, JOHN R. SPURRIER, a citizen of the United States residing at Bethlehem, in the county of Lehigh and 5 State of Pennsylvania, have invented certain new and useful Improvements in Circuit Breakers, of which the following is a specification.

This invention relates to circuit breakers 10 and is particularly adapted for use in connection with the small sizes of motors which are employed for the operation of domestic machinery.

One object of the invention is to produce 15 a compact circuit breaker adapted to handle relatively large amounts of energy. Another object is to make the device completely enclosed so as to shield its interior from tampering, to protect the device from dust and 20 dirt and to safeguard the user from contact with any parts of the device. Another object is to adapt the breaker to be conveniently closed and opened manually when desired by simple means. Another object is 25 to so relate the parts of the controlling means that in the closing of the breaker, the initial rush of current in starting the motor or other device will not cause the breaker to be opened, but after the initial rush of 30 current, any recurrence of an overload current during running conditions, would cause the breaker to be immediately opened.

This feature is especially desirable in a 35 circuit breaker for controlling motors of the character above referred to, because they are usually unprovided with any special means to reduce the starting current; and it is of course desirable that the starting current should not trip the breaker, but an overload 40 current during running conditions should of course instantly trip the breaker. Other objects of this invention will be understood from the following description and accompanying drawings illustrating a preferred 45 embodiment of the invention.

Fig. 1 is a front elevation; Fig. 2 is a side elevation; Fig. 3 is a vertical central cross section on line 3—3 of Fig. 4; Fig. 4 is a section on line 4—4 of Fig. 3; Fig. 5 is a 50 section on the line 5—5 of Fig. 4, and Fig. 6 is a section on line 6—6 of Fig. 5.

The circuit breaker is mounted upon a shallow base 1 adapted to be secured by screws on a vertical support. The elements comprising the breaker are mounted upon the base 1 and enclosed by a removable cover or casing 2. This cover is firmly held in position by U-shaped guides 3 extending inwardly from each side of the cover. Bolts 4 are firmly mounted upon the base 1 and extend outwardly from the base so as to be engaged by the guides 3 of the cover and thus hold the latter in fixed position. The cover is held firmly against the base by screws 4' which make threaded engagement 65 with the tapped outer ends of the bolts 4.

On the base 1 is mounted a flat rectangular sheet 5 of steel or other magnetic material. To the lower end of this plate 5 is secured a sheet metal piece 6 of iron or 70 steel forming the lower end frame support of the circuit breaker elements. This end piece 6 has a flat supporting portion by which it is secured to the plate 5 and has a horizontally outwardly extending portion, 75 and at its outer end a downwardly vertically extending portion 6^a. It is also provided with downwardly extending side portions 6^b, which give strength to this end frame and also serve as a support for parts later 80 referred to.

At the upper end of the plate 5 is mounted the upper end frame 7 which is in the form of a vertical supporting part by which it is secured to the plate 5 and has an outwardly 85 horizontally extending portion 7^a; it also has upwardly extending side portions 7^b.

A hollow brass tube 8 extends from the upper frame 7 through a hole in the central part of the lower frame 6. The overload 90 coil 9 is wound upon the tube 8 between the end heads. A cylindrical iron plug 10 is fixed in the upper end of the tube 8; and a cylindrical plunger 11 is freely movable in the tube and normally rests against an adjustable screw 12 in the lower end of the tube 8 and having a threaded engagement therewith. Turning the screw 12 adjusts the normal position of the plunger 11 to any desired position. The plunger 11 has a central hole in its upper end for supporting 100 a brass pin 13. The pin 13 extends freely

through a central hole in the upper plug 10 which serves as a guide for the pin.

The U-shaped lever 14 for closing the breaker is pivoted and supported at its lower ends by the side extensions 6^b of the frame 6. The upper portion of the frame 14 is semi-circular at 14^a and has an upwardly extending arm 14^b, which engages the insulating frame carrying the movable contacts. The frame and its movable contacts are spring pressed outwardly so as to tend to keep the contacts open and are retained in closed position by the arm 14. A retaining latch 16 of sheet metal is in the form of two side pieces pivoted at their inner ends to side portions 7^b of the end frame 7 at 16^a, the two side pieces of the latch being joined by a horizontally extending bridge portion 16^b which is over the plunger and pin 13 of the breaker. The outer lower end of each side piece of the latch is notched and engages the shoulders 14^c of the retaining arm 14 when the breaker is in closed position. The breaker is automatically opened when the plunger 11 is raised and the upper end of the pin 13 strikes against the portion 16^a of the retaining latch, thus releasing the arm 14 and permitting the spring pressed contacts to move quickly to open position.

In order to prevent the breaker from being automatically opened during the starting of the motor or other device controlled by the breaker, and in order to close the breaker manually, a plunger 17 is used which extends horizontally and outside the cover. The outer end of this plunger is provided with a button 17^a marked "Close" in Fig. 1 of the drawings and the plunger is supported and guided by a tube 18 fixed at its outer end to the cover and extending inwardly. The plunger 17 is provided with a cross pin 17^b which engages slots 18^a in the tube 18, for the purpose of limiting the outward and inward movement of the plunger 17. The cross pin 17^b extends outwardly a short distance beyond the tube 18 and when the plunger 17 is pressed inwardly, the outer ends of the pin 17^b engage the sides of the circumferential portion 14^a of the arm 14 and thereby forces the arm 14 inwardly until retained by the latch 16 as shown in Fig. 5. But during this closing movement, the inner end of the plunger 17 is forced inwardly so as to come in the path of the tripping pin 13; consequently during the closing of the breaker and starting of the motor or other device controlled, the passage of any overload current, which would otherwise trip the breaker, will then merely cause the pin 13 to strike against the inner end of the plunger 17 and thus prevent the tripping of the latch. When the operator releases his thumb or finger from the closing button 17^a, the plunger 17 is pressed outwardly by a leaf-spring 19, the

lower end of which is fastened to the outward end of the frame 6. The upper end of the spring 19 is circular and embraces the tube 18 and also engages the inner sides of the outer ends of the cross pin 17^b, thus tending to hold the plunger 17 in its outer position.

The breaker is manually opened when desired, by pushing the button 20 marked "Open" in Fig. 1. On the same pin through the side extensions 6^b, upon which the arm 14 is mounted, is also mounted a lever 21. This lever is made up of the two pivotally mounted side pieces, which are united by the flat portion 21^a, which latter is located opposite the inner end of plunger 20^a. The plunger 20^a is slidably mounted in the cover 2 and has the button 20 mounted upon its outer end. A leaf-spring 22 is secured at one end to the outer part of the frame 6, the outer end of the leaf spring being under a pin 20^b extending through the plunger 20^a, thus causing the plunger 20^a to be normally forced outwardly by the leaf spring 22. In the inner end of one of the side pieces of the lever 21 is pivotally mounted a rod 23, which extends upwardly and is pivotally connected at its upper end to one of the side pieces of the latch 16. Evidently pressing the button 20 causes the plunger 20^a to strike the bridging portion 21^a of the lever 21 causing the lever to turn upon its pivotal mounting in the frame 6. This causes the rod 23 to be raised and consequently raises the latch 16 and permits the breaker to open.

The fixed contacts of the breaker are mounted within the base 1 in layers 24 of fiber or other insulating material secured to the base 1 by screws 25. The leads 26 are connected to terminal blocks 27 encased in the insulating material 24. Each block 27 carries an outwardly extending portion in threaded engagement with the middle layer of insulation and form the fixed contacts 28. The fixed contacts are each separately enclosed by a tube 29 of insulating material which extends into the base 1 and have external screw threaded engagement with the outer layer of insulating material 24. The outer ends of tubes 29 are closed except for a central opening to permit the free movement of the shanks 30 of the movable contacts. Each shank 30 carries an inner circular head 30^a adapted to cooperate with the fixed contacts 28. The shanks 30 of the movable contacts have an outer portion 30^b of reduced diameter, which extend freely through the cross head 31 of insulating material. Nuts 30^c on the outer ends of the reduced portions 30^b insure that the movable contacts will be separated from the fixed contacts when the cross head 31 is thrown outwardly. Washers 30^d are located against the shoulders of the shanks 30 and

retain springs 30^a in position on the portions 30^b between the cross head 31 and the washers 30^d. These springs tend to force the movable contacts inwardly and give a yieldable engagement of the contacts in the closing of the breaker. Each insulating tube 29 is provided with a few perforations 29^a around its circumference outside of the base 1 to permit the escape of air or gases from the interior of the tubes.

In order to guide the contacts and bridge 31, a metal tube 32 is firmly mounted within the insulating layers 24 by a threaded engagement and nut 32^a. A plunger 33 freely movable in the tube 32 is fixed at its outer end to the insulating bridge 31 by a threaded engagement and thus serves as a guide in the movement of the movable contacts. A coil spring 34 encircles the tube 32 between the base 1 and a washer 32^b. This spring tends to force the breaker to open position when released by latch 16.

Below the contacts and at each side of the breaker is firmly mounted upon the base 1 an insulating tube of fiber or other material 35, being shown as secured to the base by a screw 35^a which extends through the base and engages the fiber tube. A flexible lead 36 is in electrical connection with each movable contact, respectively, by being clamped between the nuts 30^c. Each flexible lead 36 extends respectively down through the top of a tube 35 and out through a side hole therein near the base and are in electrical connection with the terminals of the overload coil 9.

In operation, the operator presses the button 17^a which forces the breaker to closed position as above explained. The circuit through the circuit breaker contacts and overload coil is obviously from one lead 26 to a fixed contact and to a movable contact; then through a flexible lead 36 to the overload coil 9 and from the overload coil 9 through the other flexible lead 36 to the other movable and fixed contacts to the outside lead 26. The operator in the closing of the breaker causes the plunger 17 to extend in the path of the tripping pin 13 so that during the flow of the starting current the breaker cannot be tripped when the pin 13 is raised during the starting period, the initial current being several times as great as the normal current. If it were not for the plunger 17 the initial rush of current would raise the tripping plunger to its extreme upper position where it would remain even after the current had fallen back to normal. The plunger 17, however, prevents the plunger from rising to its extreme position and upon the reduction of the current flow to normal amount, the plunger falls back to its normal lower position, which causes the breaker to be in condition for automatically tripping the same upon the

occurrence of any subsequent overload current, the plunger 17 being retracted by spring 19 after the operator releases the button 17^a.

Although I have described one embodiment of my invention it will be understood that various modifications may be made therein without departing from the scope of this invention.

I claim:

1. A circuit breaker comprising a controlling coil and tripping means having an upward movement for tripping the breaker, means for closing said breaker independently of said tripping means and for introducing a barrier for preventing the upward opening movement of the tripping means during the initial closing of the breaker, and means for removing said barrier upon release of the closing means.

2. A circuit breaker comprising a controlling coil, a movable plunger controlled thereby having an upward movement for tripping the breaker, means for closing the breaker independently of said plunger, a barrier controlled by the closing means for preventing the upward opening movement of the plunger during initial closing of the breaker, and means for removing said barrier upon releasing the closing means.

3. A circuit breaker comprising a controlling coil, end frames at opposite ends of said coil, retaining means mounted in one of said end frames for holding the breaker in closed position and manually controlled means mounted in the other end frame for causing the opening of the breaker.

4. A circuit breaker comprising a controlling coil, retaining means at one end of said coil for holding the breaker in closed position, means mounted at the other end of the coil for controlling the release of said retaining means, a plunger at one end of the coil for manually closing the breaker and a plunger at the other end of the coil for manually opening the breaker through said controlling means.

5. A circuit breaker comprising fixed contacts, yieldably mounted plunger contacts, a controlling coil below said contacts, a pivoted arm mounted at the lower end of said coil for closing the breaker, a latch mounted at the upper end of said coil for engaging said arm to hold the contacts in closed position, a casing enclosing the breaker and means extending outside the casing and adapted to engage said arm for manually closing the breaker.

6. A circuit breaker comprising an overload coil, a plunger controlled thereby for tripping the breaker, manual means for closing the breaker independently of said plunger, means controlled by said manual means for forming a barrier to the full movement of said plunger during the initial

closing of the breaker, and means for removing said barrier upon release of said manual means.

7. A circuit breaker comprising a controlling coil and tripping means, means for closing the breaker independently of said tripping means, means controlled by said closing means for introducing a barrier for preventing the operation of said tripping means during the initial closing of the breaker, and means whereby said barrier is removed upon release of said closing means.

8. A circuit breaker comprising a controlling coil and tripping means, means for closing the breaker independently of said tripping means, a plunger controlled by said means for preventing the operation of said tripping means during the initial closing of the breaker, and means whereby said plunger upon release of said closing means is moved to a position to permit the operation of said tripping means.

9. A circuit breaker comprising a pivoted element for closing the breaker, a latch for retaining said pivoted element in closed position, a device for tripping said latch, manually controlled means for engaging said element for closing the breaker independently of said latch, an element controlled by said means for preventing said tripping device from tripping the latch during the initial closing of the breaker, and means for moving said latter element upon release of said manually controlled means to permit the operation of said device.

10. A circuit breaker comprising contacts, a pivoted arm for closing said contacts, a handle for moving said arm to close the contacts, a latch for retaining said arm, a controlling coil, a movable element controlled

by said coil for tripping said latch, a barrier controlled by said handle for preventing the operation of said movable element during the initial closing of the breaker, and means for moving said barrier upon the release of said handle to permit the operation of said movable element.

11. A circuit breaker comprising a coil having a vertical axis, contacts above said coil, an arm pivoted at the lower end of said coil for closing said contacts, a latch at the upper end of said coil for retaining said arm, a plunger in the coil for tripping said latch, a manual element for moving said arm, a barrier for preventing the movement of said plunger during the initial closing of the breaker, and means for removing said barrier after the breaker has been closed.

12. A circuit breaker comprising a controlling coil and tripping means having an upward movement for tripping the breaker, a push button for closing said breaker, a second push button for opening the breaker, a barrier controlled by the closing button for preventing the upward movement and tripping of the breaker during the initial closing of the breaker, and means for moving said barrier to permit operation of the tripping means upon release of the closing button.

13. A circuit breaker comprising a controlling coil, end frames at opposite ends of said coil, retaining means mounted in one of said end frames for holding the breaker in closed position, means mounted in the other end frame for causing the opening of the breaker, and a push button for controlling said last named means for causing the opening of the breaker.

JOHN R. SPURRIER.
